UNITED STATES PATENT OFFICE

EDWIN D. TILLSON, OF EVANSTON, ILLINOIS, ASSIGNOR TO SOMERVILLE W. THOMPSON,
TRUSTEE, OF CHICAGO, ILLINOIS

DESIGN FOR A BOWL FOR INDIRECT-LIGHTING FIXTURES

Application filed March 30, 1929. Serial No. 30,687. Term of patent 14 years.

To all whom it may concern:

Be it known that I, EDWIN D. TILLSON, a citizen of the United States, residing at Evanston, in the county of Cook and State of Illinois, have invented a new, original, and ornamental Design for a Bowl for Indirect-Lighting Fixtures, of which the following is a specification, reference being had to the accompanying drawings, forming part thereof.

Fig. 1 is an elevation of a bowl for indi-

rect lighting fixtures, showing my new design, with only a partial representation of the ornamental border which extends entirely around the bowl.

Fig. 2 is an enlargement of the ornamental border portion forming a portion of the design shown in Fig. 1.

I claim:

The ornamental design for a bowl for indirect lighting fixtures as shown.

EDWIN D. TILLSON.
